UNITED STATES PATENT OFFICE.

WARREN F. FRASER, OF WESTBORO, MASSACHUSETTS, ASSIGNOR OF ONE-HALF TO
MORRIS GREEN, OF NEW YORK, N. Y.

ALARM LOCK.

Application filed October 18, 1922. Serial No. 595,346.

My invention relates to an alarm lock and more particularly to a lock which will sound an alarm when an unauthorized attempt is made to force the lock or operate it improperly.

Numerous cunning methods are being constantly devised by the criminal classes for gaining entrance to houses where wealth is supposed to be concealed. The problem of thwarting such activities is becoming increasingly difficult, owing particularly to the overcrowded living conditions found in the cities which appeal to one type of thief, and on the other hand to the isolation of country homes where a burglar may work in comparative safety for a considerable length of time.

Various types of devices have been proposed for giving an alarm when a lock is being tampered with, since a considerable proportion of burglaries are effected through opening a locked door. Such devices have been found unsatisfactory or commercially unfeasible owing to defective or expensive construction or to their not furnishing adequate protection at all times against the methods ordinarily employed in housebreaking. One common method is to operate the lock by means of a skeleton key, and a key worker is usually equipped with a large number of such types of keys, which he can quickly try in the lock. Electrical apparatuses have been devised to give a signal when a lock combination is not known or when the wrong key is employed, but these serve to give an alarm only while the lock is being tampered with. Consequently, when the burglar cautiously tries the lock, he is immediately warned by the alarm and can stop the ringing bell merely by desisting from such methods and devising others. If the first momentary sounding of the bell has not been heard by the house occupants, no notice of the attempt is received which will aid in the capture of the thief. Moreover, such electrical devices have been too complicated in construction to be commercially feasible, or they have been inadequate to warn of the use of force as well as skill in trying to open the closure.

Devices have been suggested which will give a signal when a door is being jimmied, but these have been so constructed that after the tool intended to force the door open has been withdrawn the alarm will no longer

sound. These devices as proposed, while embodying some desirable elements, have not combined therein sufficient or the right types of safety features to give an incessant alarm either locally or at a distance from the door when one who does not possess the right key attempts an unauthorized entrance either by trying various keys or by forcing the door open. If an alarm lock protects merely against the use of the wrong key, or against the use of force alone, there is of course an equal chance that the thief employs the method not covered by the device, and the protection is inadequate.

It is accordingly one object of my invention to overcome the disadvantages and mechanical imperfections of the prior constructions and to provide a combination alarm and lock which is capable of satisfying the insurance and commercial requirements of a burglar proof lock and otherwise to provide a simple and economical construction which is easily built and quickly installed, and will give an incessant alarm which cannot be stopped from outside the door when an improper attempt is made to open the same.

Further objects of my invention are to provide a combination safety alarm lock which, if the wrong key is used therein in an attempt to open the lock or excessive lateral pressure is applied to force the lock open, will sound an incessant alarm to warn of the tampering with the lock and to provide simplified mechanical constructions capable of accomplishing either of these results alone by sounding an alarm either locally or at a distance.

Still further objects of my invention are to provide a mechanical wind up alarm and a door lock comprising a key controlled tumbler device so constructed that an adequate alarm will be sounded at the door by any tampering with the lock and to combine therewith an electrical alarm device which will simultaneously give a warning at a distance from the door, when the wrong key is used or an attempt is made to force open the closure.

With these and other objects in view as will be apparent from the following disclosure, my invention resides in the combination of parts set forth in the specification and covered by the claims appended hereto.

Referring to the drawings in which like

reference numerals indicate like parts

Fig. 1 is a section on line 1—1 of Fig. 2, with various parts shown in elevation;

Fig. 2 is a section on the line 2—2 of Fig. 5 1, including in dotted outline that portion of the door casing which cooperates with the lock bolt to hold the door;

Fig. 3 is a sectional detail of the tumbler mechanism;

10 Fig. 4 is a section on the line 4—4 of Fig. 3;

Fig. 5 is a rear view of the locating plate and the lock parts shown in Fig. 3;

15 Fig. 6 is an elevation partly broken away to show a detail of the bolt mechanism and trunnion mounts therefor; and

Fig. 7 is a diagrammatic perspective view of important features of the device, showing the manner of its operation.

20 The usual lock comprises a bolt operated by a key controlled tumbler device in which a rotary barrel mounted in an outer tumbler casing is locked by a double set of tumblers and can be turned to operate the lock bolt only when the tumblers are correctly positioned by the right key.

In accordance with one aspect of my invention, I so construct a lock of this general type as to release an alarm when the lock 30 is improperly operated. This may be accomplished by mounting the rotary barrel so that if the wrong key is inserted and an attempt is made to turn the barrel when the tumblers are still in a locking position, the torque is transmitted to sound an incessant alarm, i. e. one of long duration, either locally through a mechanical device or at a distance by electrical apparatus, or by both types, and particularly to release 40 a mechanical wind up device and make an electric circuit with an electric bell and battery. While the invention in its broader aspects, as determined by the scope of the 45 appended claims, applies to locks for various uses, such as on an automobile to hold some movable part of the machine, I have merely illustrated and described its applicability to closures or doors of houses.

To accomplish this end, and as one embodiment of the invention, I may mount the tumbler barrel for movement relative to a tumbler casing which is also yieldingly movable. This casing which preferably surrounds the barrel and is rotatable thereon, 50 is mechanically connected with the alarm mechanism; and I so construct and arrange the parts that a single movement of the casing will effect a permanent release of the alarm mechanism without moving the locking bolt far enough to affect the security of the lock. To provide for sounding an alarm when transverse pressure is applied against the lock in such cases where it is used on a closure, I may mount the bolt or its supports in such a manner that a yielding trans-

verse movement of the bolt relative to the closure is permitted, this also releasing the alarm mechanism. This may be particularly accomplished by mounting the bolt housing on trunnions for swinging movement and resiliently holding the housing in an inoperative position under the slight pressures normally applied for opening a door. Similarly, the key and tumbler alarm controlling mechanism is resiliently held so that the ordinary friction of turning the lock with the proper key will not sound an alarm, but it is preferably so arranged that an improper use even of the right key will release the alarm. In order to give an alarm at a distant station as well as locally I may also provide the mechanism with electrical contacts connected with electric bells and annunciators or similar apparatus.

As illustrated in the drawings, I may combine the various features of my invention in a unitary and simplified construction of a mechanical and electrical alarm lock suitable for a door. In the exemplified construction, I employ a key and tumbler device 85 which differs from the usual lock of this type in that the barrel 10 is mounted for rotation relative to a tumbler casing 11 which is also mounted for rotative movement with the barrel. The barrel 10 which carries the 90 casing 11 is supported by a cup-shaped, flanged member 12 suitably inserted in a hole in the door and fastened thereto as by means of a rear plate 13, (Figs. 1 and 5) fixed on the inside of the door and bolted 95 to the plate 14 fastened to the flanged cup 12 by bolts 15. As is well known in this art, the rotary barrel 10 is provided with 100 sockets 16 which may be aligned with similar sockets 17 mounted in the outer rotary 105 casing 11. Two sets of tumblers 18 and 19 are located in the sockets, these being of such 110 lengths relative to the shape of the key 20 that when the right key is properly inserted in the key slot 21 which intersects the bottoms of the sockets in the barrel, the lugs on the key will raise the tumblers against the pressure of springs 22, located in the upper ends of the sockets 17, and all the tumblers will be positioned with their inner 115 rounded faces substantially coinciding with the peripheral surface of the rotary barrel 10, so that the barrel may be rotated by turning the key. If the wrong key is used, obviously some of the tumblers will overlap 120 the parting plane between the barrel and its casing and so prevent turning of the barrel relative to its casing 11. Loosely fastened to the end of the barrel 10 is a shank 23 which is adapted to operate the lock bolt 125 mechanism. The end of the shank projects into a recess in the end of cylinder 10 and has a slot 24 engaged by a projecting lug on a clip 25 screwed to the barrel. (Fig. 3.)

The door bolt or latch and its associated 130

parts may be of suitable construction except as modified to accomplish the desired results. As shown particularly in Fig. 6, the bolt 26 which projects through a hole 27 in the housing 28 may be provided with two parallel slide members 30 which are slidably mounted in a plate 31 fixed within the housing. Springs 32 surround the slides and tend to maintain the bolt 26 in an outside locked position. In order to retract the bolt, a plate 34 is mounted on the rear plate 35 (Fig. 1) for movement by the shank 23. This plate 34 is rotatably mounted on plate 35 by means of a bushing 36 inserted in a hole in the plate 35. The plate 34 has cams 38 so arranged and positioned as to ride against the lugs 39 fixed on the ends of the slides 30. By this construction it can be seen that turning the plate 34 in either direction by means of the shank 23 causes the cams 38 to push back on the lugs 39 and withdraw the bolt from its locked position. In order to combine a bell clock work mechanism with the lock I mount the housing 28 on a base 25 or casing 40, this casing having an extended plane portion 41 on which is secured the alarm mechanism.

While I may employ various types of mechanical alarms within the scope of my invention, I have indicated in the drawings a well known form of wind up clock work and bell mechanism which is suitable for my purpose. As shown, the bell 43 is freely mounted for vibration on the bushing 44 which is fastened to a plate 45. This plate is mounted on posts 46, fastened to the rear plate 47 which in turn is suitably fixed on the support 41. The bell is secured on the bushing by a screw threaded collar 48 which 40 engages a reduced portion of the bushing passing through a central aperture in the bell. A bell hammer 50 pivotally mounted on the post 51 is operated by means of a wheel 52 which is rotated by a spring driven mechanism. Each of the pins 54 projecting from the sides of the wheel 52 is adapted when revolved to engage the bent up end 55 of the bell hammer lever, as illustrated in Fig. 2, and lift the hammer 50 against the 45 action of gravity and a spring 56 and then release it for a stroke against the bell. I have shown three pins 90 degrees apart on the wheel 52, the fourth pin being omitted so that three taps will be given on the bell 55 followed by a period of silence so as to make the alarm more noticeable.

The alarm once released operates in this intermittent fashion incessantly until it is silenced either by the spring running down 60 or by a control lever operated from inside the door. This control lever 58 is preferably L-shaped and pivotally mounted on the post 59 with its long arm projecting upwardly above the bell for manipulation. The short arm 60 of the lever normally projects be-

neath the short arm 55 of the bell hammer and may be supported in such a position as to hold the bell hammer inoperative and prevent it being raised to permit the wheel 52 to revolve.

The wheel 52 is driven by a set of clock work gears and pinions which may be of well known construction. The intermediate geared members 61 and 62 which are operatively connected with wheel 52 are driven 70 by a bull gear 63 fixed on a rotatable post 64 and adapted to be driven by the spring 65. The spring 65 which is held stationary at one end and connected to the gear 63 at the other end is wound up by means of the usual 75 construction comprising a winding key 67 attached to the post 64. Unwinding of the spring is prevented by a spring pressed pawl 80 and ratchet 69.

In order to combine the various features 85 so far described into a unitary mechanism for giving a desired alarm, I may utilize the arrangement of parts illustrated in the drawings. The lever arm 60 is pressed against the bell hammer arm 55 to hold it in 90 the path of one of the pins 54 by means of a rocking arm or trigger 70 mounted beneath lug 71 which projects laterally from the arm 60, these parts being so constructed and arranged that displacement of the arm 70 from a normal holding position, which is shown in the drawing, will permit lever arm 60 to fall downward under the action of gravity or a spring if desired, and release the wheel 52 and permit it to operate the 95 bell hammer. In order to connect the rocking arm 70 with the two essential portions of the lock, I fasten it to a rod 72 mounted to rotate on pivots 73, which are screw threaded into opposite portions of the casing 40 and engage bearing sockets 74 in the rod. A pin 75 projecting laterally from the rod 72 has its outer end passing loosely through a hole 76 in a slide plate 77. This slide is secured in a vertically movable position by means of headed screws 78 passing through elongated narrow slots 79 in the slide and threaded into a portion of the support 40. Movement of the slide will swing arm 70 to one side and permanently release 100 the alarm.

The slide 77 is operably connected with the outer rotary tumbler casing 11 by means of lugs 80 projecting rearwardly from a central portion of the slide, which is enlarged to provide for an aperture 81 through which the shank 23 passes. The slide 77 is adapted to be lifted by means of a rocking plate 83 engaging the lugs 80. This plate is threaded on the projecting end of a hollow cylinder 84 which telescopes with another hollow cylinder 85 and to which it is keyed by projecting lugs 86 on cylinder 84 riding in slots 87 in the other cylinder. As shown particularly in Fig. 1, cylinder 84 110 115 120 125 130

is mounted for rotation in an aperture in the plate 13 and endwise movement is prevented by plate 83 and flange 88 which engage opposite sides of plate 13. This telescoping connection is employed to accommodate different thicknesses of door. The inner smaller cylinder 85 is fastened to the rear of the rotatable tumbler casing 11 by means of screws 90 passing through lugs 91 on the casing 11 and engaging a thickened portion of the cylinder 85 which engages the rear of plate 14 and holds this part in place.

The tumbler casing 11 is rotatably mounted on the inner cylinder 10, the latter in turn being supported at its front end by the flanged cup 12 and at the rear end by the cylinder 85 and plate 14. The casing 11, which is shaped like a cylinder provided with a projecting flange or key as shown in Fig. 4, is resiliently held in a central position by means of the U-shaped spring 93 which surrounds the cylinder, pressing against the ends of the flanged portion thereof and an inwardly depending lug 94 formed on the interior of the cup 12.

It will therefore be seen that if the tumblers are not correctly positioned when an attempt is made to turn the lock, the casing 11 will be turned against the resilient action of the spring 93, thus rotating the telescoping cylinders and the plate 83, which results in an upward pressure on one of the lugs 80, and moves plate 77 and the rocking arm 70. A certain degree of freedom may be provided so that a slight motion of the casing 11 will not set off the alarm, but as illustrated it will not take much movement thereof to permit the lever arm 60 to fall down beside the rocking arm 70. It will also be clear that once the lever arm 60 has fallen nothing can be done from outside the door to stop the alarm. When the alarm has been released, the arm 70 cannot get under the lug 71 until the lever 58 is moved by hand, after which the weight of the slide and associated parts will swing arm 70 to a locking position.

In order to release the alarm when excessive lateral pressure is applied to the door, as by an attempt to jimmy the lock, I mount the locking bolt 26 for lateral movement which may be communicated to the lever arm 60. In the construction illustrated the housing which carries the slidable bolt is made movable for this purpose. To this end, I provide the housing 28 with trunnions 96 which are pivotally mounted in sockets 97 provided in the casing 40 which for the purpose of assembling may be made in two or more parts and fastened together as by means of screws to form a suitable supporting base for the various parts.

Springs 98 secured to the plate 41 project downwardly and resiliently press against the rear of the housing 28 on each side of the

trunnions so as to hold the housing normally in a central position. L-shaped arms 99 fixed to and depending from the rod 72 contact with springs 98 adjacent the housing 28. It will therefore be seen that if the housing 28 swings about its trunnions in either direction the rocking arm 70 will be moved from its holding position and so release the alarm. The springs 98 are given sufficient rigidity to prevent the alarm being sounded by ordinary usage of the door. Rotation of the housing relative to the shank 23 is permitted by having the shank fit loosely in its associated parts within the lock.

The alarm mechanism so far described will sound an alarm locally at the door. If it is desired to give a distant signal I may utilize an electric bell or buzzer in circuit with a source of electrical energy and a switch adapted to be closed by anyone tampering with the lock, and I preferably so arrange the parts that the switch arm may be held normally in a raised position by a trigger, such as rocking arm 70, and released to close the circuit by movement of the trigger. I may also combine the electrical alarm with a mechanical local alarm, as illustrated in the drawings, but it is to be understood that in a simplified apparatus it is feasible to employ either type of alarm alone.

To combine an electrical device with the structure above described, I attach a terminal wire 100 to a post 101 suitably fastened on the casting 40 and in electrical contact therewith. The other terminal 102 is attached to a switch which is adapted to be closed by improper attempts at opening the door. In the switch illustrated I make use of the lever arm 60 for one contact element. The wire 102 is suitably connected with a contact 103 mounted on a post 104 which is fastened to and insulated from the casing, as shown in Fig. 1. This contact is located below and spaced from a similar contact 106 mounted on the lever arm 60, these parts being so positioned that when the lever arm is released and falls down, an electrical circuit is made through this contact and the metal bearing of the arm 60 and the post 59. Various electrical devices and arrangements may be employed as is obvious to one skilled in this art. I have illustrated an electric bell 108 and an annunciator 109 of any well known construction, in line with the battery 110 so that a continuous alarm will be given when the lever arm 60 falls, and the location of the attempted housebreaking may be determined by the annunciator.

The operation of this device will be obvious from the above description. It also will be evident that various changes may be made in this construction within the scope of the appended claims and that the invention may be applied to various mechanisms which require to be locked. In each case I may

not need to use all of the elements associated in the door lock above described but I will select those features which are particularly applicable to accomplish the desired end.

5 Having thus described my invention, what I claim as new and desire to secure by Letters Patent is:-

1. An alarm lock for a closure comprising an alarm mechanism, releasable holding means to maintain it normally inoperative, a reciprocable lock bolt, a tumbler and key device connected to operate the bolt, a movable support for said device, yielding means to hold the support normally immovable 15 when the right key is properly used and permit movement thereof when the wrong key is forcibly used, and mechanical connections between said support and holding means actuated in one direction only by movement of 20 the support to release the alarm mechanism.

2. An alarm lock comprising a reciprocable bolt, a key and tumbler device including a rotary barrel, a yieldingly movable tumbler casing surrounding the barrel and 25 key operated tumblers which permit rotation of said barrel relative to the casing when the tumblers are correctly positioned by the use of the right key, connections from the barrel to operate the bolt, a mechanically operated bell and clock work mechanism for 30 sounding an incessant alarm, a trigger device capable of being set to restrain operation of said mechanism and independent connections between said casing and said trigger device to move the latter and release the alarm when the casing is moved with the barrel by the use of the wrong key and permit return of the barrel to a normal position 35 without stopping the alarm.

40 3. An alarm lock comprising a clock work alarm mechanism, a reciprocable bolt, a key controlled tumbler device connected to reciprocate the bolt, a locking device effective to hold the alarm mechanism normally inoperative, means operated by the use of the wrong key to move said device and thereby cause an incessant alarm and manually operable means independent of the tumbler device to reset the locking device and hold the alarm mechanism in an inoperative condition.

45 4. An alarm lock for a closure comprising an alarm mechanism, a trigger device to hold the same normally inoperative, a reciprocable and laterally movable bolt, means permitting lateral movement of the bolt only under excessive pressure, a key controlled device to reciprocate the bolt normally, and connections between the bolt and the trigger device operable by lateral movement of the bolt to release said mechanism and thereby sound an incessant alarm.

50 5. An alarm lock for a closure, comprising an alarm mechanism normally held inoperative, a reciprocable bolt, a key controlled

tumbler device connected to reciprocate the bolt, a support for the bolt capable of lateral movement, and means connecting said support and alarm mechanism effective to sound an incessant alarm when said support 70 is moved by excessive lateral pressure applied against the closure.

6. An alarm lock comprising a bell and spring operated clock work mechanism for sounding an incessant alarm, a releasable 75 trigger to hold the same normally inoperative, a reciprocable bolt, a laterally movable support therefor, resilient means to restrain lateral movement of said support, a key and tumbler device connected to reciprocate the bolt and operative connections between said support and trigger to release the latter and give an incessant alarm when the bolt support is moved momentarily in a 80 lateral direction.

7. In combination with an alarm, a reciprocable locking bolt, a base, a housing for the bolt having trunnions pivotally mounted on the base, resilient means to permit yielding movement of said housing, a key controlled device connected to operate the bolt, a releasable trigger which normally holds the alarm mechanism inoperative and connections between said housing and trigger which move the latter and release the alarm 95 when force is applied to move the bolt housing laterally.

8. An alarm lock for a closure comprising a bolt which is movable normally into and out of a locked position as well as movable 100 laterally under abnormal pressure applied against the closure to force it open, a key controlled tumbler mechanism to lock and unlock the bolt, an alarm mechanism, means which will normally restrain said mechanism from sounding an alarm, means operable by said lateral movement of the bolt which will release the alarm restraining means and means operable by the use of the wrong key on the tumbler mechanism 105 to release said restraining means.

9. An alarm lock for a closure comprising a bolt which is movable into and out of a locked position as well as laterally, means restraining the lateral movement thereof 110 except under excessive pressure, a key controlled tumbler mechanism to lock and unlock the bolt without sounding the alarm, an alarm mechanism, means which will normally restrain said mechanism from sounding an alarm, means operable by lateral movement of the bolt which will release the alarm restraining means, and manually operable means to reset the releasable means after the alarm has been 115 sounded.

10. An alarm lock for a door comprising a bolt mounted for reciprocatory and lateral movement, a key controlled tumbler device connected to reciprocate the bolt, an alarm 120 125 130

mechanism, a releasable trigger device which normally holds the alarm inoperative, means operable by lateral movement of the bolt to move said trigger device, and independent means operable by use of the wrong key to move the trigger device.

11. In combination with a door frame and a door, an alarm lock for the door comprising an alarm mechanism, a trigger device which maintains the same normally inoperative, a reciprocable and laterally movable bolt, a key controlled tumbler device connected to reciprocate the bolt, a resiliently mounted casing for the tumbler device which is movable only by forcible use of the wrong key, means operated by lateral movement of the bolt to move the trigger device and means operated by movement of the casing to operate the trigger device positively, whereby an incessant alarm is sounded upon an attempt to utilize the wrong key in the lock, or when the bolt is moved laterally relative to the frame.

12. An alarm lock for a door comprising an alarm mechanism, a reciprocable and laterally movable bolt, a key controlled tumbler device to reciprocate the bolt, a movable casing for said device, a member arranged to be manually set to prevent operation of the alarm mechanism, a trigger releasably holding said member in position during normal operation of the bolt, connections between the casing and said trigger to move the latter when the casing is moved by improper force applied to the tumbler device, and means resiliently opposing lateral movement of the bolt which is capable of releasing said trigger if the bolt is moved laterally.

13. An alarm lock for a door comprising an alarm mechanism, a movable trigger

normally holding said mechanism inoperative, a reciprocable and laterally movable locking bolt, resilient means holding the bolt from lateral movement, a key controlled tumbler device having an inner rotary barrel connected to reciprocate the bolt and a rotary outer casing which has co-operating sets of tumblers arranged for locking the barrel to the casing except when positioned by the right key, a spring to hold the outer casing against movement during normal usage of the lock connections from the casing to the trigger to release the latter when the wrong key is used and separate connections from the laterally movable bolt to the trigger arranged to release the alarm when excessive pressure is applied laterally against the bolt.

14. An alarm lock for a door comprising a wind up alarm mechanism having a bell hammer and means to operate the same, a releasable rocking arm adapted to prevent movement of the hammer, a reciprocable bolt, a housing therefor mounted on trunnions for lateral movement of the bolt, a key controlled device to operate the bolt including a rotary barrel, tumblers and a rotary tumbler casing, a spring adapted to hold said casing normally stationary and permit the barrel to turn when the right key is used, a slide operatively connected with the rocking arm to move the same, operative connections to move the slide when the tumbler casing is rotated and means moved by rotation of the bolt housing to move the rocking arm, whereby an incessant alarm is produced by use of the wrong key or lateral pressure on the bolt.

Signed at Westboro, Massachusetts, this 80
fourth day of August, 1922.

WARREN F. FRASER.
